Attorney

UNITED STATES PATENT OFFICE.

LEONARD BRANHAM, OF ORLANDO, FLORIDA.

PIPE-WRENCH.

1,168,999.

Specification of Letters Patent.

Patented Jan. 18, 1916.

Application filed November 18, 1915. Serial No. 62,196.

To all whom it may concern:

Be it known that I, LEONARD BRANHAM, a citizen of the United States, residing at Orlando, in the county of Orange and State 5 of Florida, have invented certain new and useful Improvements in Pipe-Wrenches, of which the following is a specification, reference being had to the accompanying drawings.

10 My invention relates to wrenches, and particularly to wrenches designed for turning pipe.

15 The general object of my invention is the provision of a wrench having fixed and movable jaws, and the provision of means in connection with the movable jaw whereby it may be readily adjusted to close upon the object operated on.

20 A further object of the invention is to provide for operating the jaws while the wrench is in use and by the hand of the operator which grasps the wrench, and a further object in this connection is to provide means whereby no strain comes upon 25 the pivots whereby the movable jaw is linked to the operating handle so that these pivot pins or rivets will not bend under strain.

Other objects will appear in the course of 30 the following description.

My invention is illustrated in the accompanying drawings, wherein:

Figure 1 is a side elevation of my improved wrench, partly in section; Fig. 2 is 35 a transverse section of the wrench.

Referring to these figures, 10 designates the shank of a wrench having at one end the angularly disposed jaw 11 formed with the usual teeth 12. The inside face of this 40 jaw below the teeth 12 is formed with a recess 13 and below this recess the shank 10 is formed with the integral outwardly extending arm 14 which is bifurcated as at 15 for nearly its entire depth.

45 Pivoted within the recess 13 is a movable jaw 16 which is toothed upon that face which confronts the teeth 12, this jaw at its rear extremity being reduced in thickness and this reduced end being inserted within 50 the recess 13 and being pivoted to the shank 10 by means of the pivot pin or rivet 17. The under edge face of the jaw 16, that is, that edge face which confronts the handle end of the wrench, is formed with a recess 55 18.

Pivots mounted between the portions

15 of the arm 14 is a handle 19. This handle at one end is angularly extended to provide an ear 20 which extends up between the portions 15 and is pivoted thereto by 60 means of the pivot pin 21, rivet or like device. The upper end of the handle rearward of the extension 20 is recessed, as at 22, and having its end pivoted in this recess is a link 23, the opposite end of which is 65 pivoted within the recess 18 of the movable jaw 16. The length of the link 23 is such that when the handle or actuating member 19 is closed against the shank 10 the jaw 16 will be held in an approximately parallel 70 relation to the jaw 11 and that when the handle 19 is turned outward as far as possible the extremity of the jaw 11 will bear against the extremity of the extension 20.

As will be particularly noted from Fig. 75 1, the opposite ends of the link 23 bear at all times against the walls of the recesses 18 and 22, respectively. As a consequence no strain comes upon the pivot pins 24 and 25 whereby the link is connected to the movable jaw and to the handle. Thus there is no danger of the pivot pins giving away under strain and all pressure comes directly upon the link.

It will further be noted that by my particular construction I secure a great leverage on the movable jaw 16 and that the jaw is held closed against an object by the pressure of the operator's hand around the shank 10 and the handle 19 and that it is a 90 relatively easy matter to relieve this pressure by slightly opening the hand and then reapplying this pressure by closing the hand. Thus the wrench may be used for turning sections of pipe, couplings or like 95 articles without removing the wrench from its engagement but simply by oscillating the wrench. It is of course obvious that the wrench may be equally well used for removing bolts and in other ways applied in the 100 manner common to wrenches. It will be seen that the movable jaw is held from any sidewise movement under strain not only by having its reduced end inserted within the recess 13 but by the further fact that 105 the link 23 fits relatively closely between the arms 15 and is guided thereby, and that lateral strain placed upon the movable jaw which would tend to bend it is resisted by the body of the link itself.

110 While I have illustrated a construction wherein the movable jaw 16 is spaced from

the fixed jaw 11 even when the handle 19 is pressed flat against the shank 10, it will be obvious that the movable jaw may be pivoted thereon to the fixed jaw and thus 5 the two jaws may be brought approximately together. I do not wish to be limited to the particular form of the jaws as these might be modified to suit any special class of work.

10 Having described my invention, what I claim is:

15 1. A wrench of the character described including a shank having a fixed jaw, a movable jaw pivoted to the shank, said shank having an outwardly projecting arm below the movable jaw, a handle pivoted to said arm and being thereby movable toward or from the shank, and a link pivoted to the upper end of the handle between the free 20 end thereof and its point of pivotal connection to the arm, the upper end of the link being pivoted to the movable jaw.

25 2. A wrench of the character described including a shank having a fixed jaw, a movable jaw pivoted to the shank, said shank having an outwardly projected bifurcated arm disposed below the movable jaw, a handle having an extension pivoted in said bifurcated arm, said handle being thereby 30 movable toward or from the shank, and a link pivoted to the upper end of the handle, passing upward through the bifurcated arm and pivoted to the movable jaw.

35 3. A wrench of the character described including a shank having at one end a fixed jaw and recessed adjacent the fixed jaw upon its inside face, a movable jaw having a reduced portion disposed within said recess

and pivoted to the shank, said shank below the movable jaw being formed with a bifurcated arm, a handle having an upward extension pivotally mounted in the extremity of the bifurcated arm, the upper end of the handle inward of said extension being recessed and the confronting face of the movable jaw being also recessed, and a link having its ends inserted in said recesses and pivoted operatively to the handle and jaw, said link passing through the bifurcated arm and being guided thereby. 50

4. A wrench of the character described including a shank having at one end a fixed jaw and recessed adjacent the fixed jaw upon its inside face, a movable jaw having a reduced portion disposed within said recess and pivoted to the shank, said shank below the movable jaw being formed with a bifurcated arm, a handle having an upward extension pivotally mounted in the extremity of the bifurcated arm, the upper end of the 55 handle inward of said extension being recessed and the confronting face of the movable jaw being also recessed, and a link having its ends inserted in said recesses and pivoted operatively to the handle and jaw, said link passing through the bifurcated arm and being guided thereby, the extremities of said link bearing at all times against the walls of the recesses in the movable jaw 60 and handle respectively. 70

In testimony whereof I hereunto affix my signature in the presence of two witnesses.

LEONARD BRANHAM.
